(57) **CLAIM**

The ornamental design for an air conditioner, as shown and described.

DESCRIPTION

FIG. 1 is a perspective view of front, right and bottom side of an air conditioner showing a first embodiment of my new design;

FIG. 2 is a front view thereof;

FIG. 3 is a rear view thereof;

FIG. 4 is a right side view thereof, a left side view is a mirror image thereof;

FIG. 5 is a top view thereof;

FIG. 6 is a bottom view thereof;

FIG. 7 is an enlarged cross sectional end view of cutting part at 7-7 in FIG. 2 omitting the interior mechanism; and

FIG. 8 is a perspective view of front, right and bottom side of an air conditioner showing a second embodiment of my new design;

FIG. 9 is a front view thereof;

FIG. 10 is a rear view thereof;

FIG. 11 is a right side view thereof, a left side view is a mirror image thereof;

FIG. 12 is a top view thereof;

FIG. 13 is a bottom view thereof; and,

FIG. 14 is an enlarged cross sectional end view of cutting part at 14-14 in FIG. 9 omitting the interior mechanism.

The portions of the article in broken lines are shown for illustrative purposes only and form no part of the claimed design.
